ELECTRICAL DISCHARGE DEVICE

William W. Eitel and Jack A. McCullough, San Bruno, Calif., assignors to Eitel-McCullough, Inc., San Bruno, Calif., a corporation of California

Application February 11, 1942, Serial No. 430,389

3 Claims. (Cl. 250—27.5)

Our invention relates to a discharge device such as a thermionic tube; and more particularly to a mounting structure for an electrode in the tube.

It is among the objects of our invention to provide improved means for supporting an electrode on a lead extending through a stem of an envelope.

Another object is to provide means for shielding the stem against electron bombardment and heat radiation.

A further object is to provide an improved lead adapted for directing a cooling fluid into the stem.

The invention possesses other objects and features of advantage, some of which, with the foregoing, will be set forth in the following description of our invention. It is to be understood that we do not limit ourselves to this disclosure of species of our invention, as we may adopt variant embodiments thereof within the scope of the claims.

Referring to the drawing:

Figure 1 is a side view, partly in section and partly in elevation, showing a grid mounting structure embodying the improvements of our invention; and

Figure 2 is an axial sectional view showing a modified structure.

In terms of broad inclusion, our electrical discharge device comprises an envelope having a stem, a lead extending through the stem, an electrode, a shield for the stem, and means for supporting the electrode and shield on the lead. An improved lead is also provided for directing a cooling fluid into the stem.

In greater detail, and referring to Figure 1 of the drawing, our device comprises a glass envelope 2 having a reentrant stem 3 for supporting an electrode 4 such as a grid. The envelope may be of any suitable shape, say a spherical bulb; and in the device illustrated the stem projects from a side of the envelope at an angle to the axis of electrode or grid 4. For purposes of illustration we show a grid having a plurality of vertical wires welded to a base ring 6 about which is disposed a heat radiating flange 7.

A plurality of say three tungsten leads 8 extend through the stem, and are sealed in a tri-lobed pinch 9 at the nose of the stem. These leads project from the stem, with the inner ends terminating in a plane lying transversely of the stem axis. The outer ends of leads 8 terminate within the stem shortly below the press and are connected to heavier extension

leads 11 of say copper. Copper is a good thermal conductor and the extension leads serve to conduct heat rapidly out of the stem to terminal button 12 lying outside the stem cavity.

5 The mounting structure for the electrode comprises a tubular arm 13, preferably of tantalum, disposed coaxially with the stem and having an upwardly bent arcuate flange 14 welded to the circumference of base ring 6 of the grid. Since a cathode disposed within the grid usually has downwardly extending leads, the lower forward portions of tubular arm 13 are preferably cut away along the line 16 to give clearance for the cathode leads. Arm 13 10 is supported on leads 8 by a cup-shaped mounting plate 17, preferably of tantalum, welded to the ends of the leads and disposed transversely within the arm with its flanged edge welded to the arm. This structure provides a mechanically strong support for the electrode; the tubular shape of the arm not only adding to the rigidity of the support, but also providing a large radiating surface for dissipating heat before it reaches the stem by conduction. In order to increase radiation from the arm its outer surface is preferably roughened.

15 The stem structure is further protected against electron bombardment and heat radiation from the electrodes by a shield 18. This shield is also supported on leads 8; preferably being welded to the rear end of arm 13 so that the shield forms an extension of the arm. The tubular shield projects rearwardly and preferably flares outwardly to provide a protective hood about the leads and stem, with the inner surface of the shield freely spaced from the stem. Since the shield does not form part of the electrical conducting path between leads 8 and the electrode, any suitable metal such as 20 nickel may be employed for it. The outer surface of the shield is left shiny to provide a heat reflector.

25 By the structure thus described, the stem and the leads projecting from it are protected against electron bombardment and heat radiation from the electrodes. Furthermore, the shield which is exposed to the bombardment and radiation is thermally isolated from the stem since the only 30 conducting path between the two is the round-about one through the leads. The stem is thus kept sufficiently cool to prevent cracking the glass at the seal.

35 Figure 2 shows a modified construction in which a single heavy tungsten lead 19 extends through a seal 21 on stem 3. A flanged collar 22

of tantalum is welded on the inner end of the lead and to the face of mounting plate 17. In this arrangement lead 19 lies coaxial with the stem and with arm 13.

The outer extension lead 23 is preferably of copper tubing having side openings 24 within the stem, and terminating in an open ended button 26 lying outside the stem cavity. This hollow lead provides a passage through which a cooling fluid, such as air, may be directed into the stem and discharged into the stem cavity through openings 24. The air circulating back out through the mouth of the stem carries away heat and thus further cools the stem. Air may be supplied from any suitable source, and is delivered through a suitable tube connected to the outer end of the lead.

We claim:

1. An electrical discharge device comprising an envelope having a stem, an electrode, a lead for the electrode projecting from the stem, a tubular arm mounted on and extending forwardly of the

lead and carrying said electrode, and a tubular extension on the arm projecting rearwardly alongside the lead and providing a protective hood for the stem.

5. 2. An electrical discharge device comprising an envelope having a stem, a grid in the envelope and disposed about an axis angularly disposed to the axis of said stem, a lead projecting from the stem, a tubular shield embracing the stem and providing a protective hood therefor, and means supporting the shield and grid on said lead.
10. 3. An electrical discharge device comprising an envelope having a stem, an electrode in the envelope, a lead projecting from the stem, an arm extending forwardly of the lead and carrying said electrode, a shield extending rearwardly alongside the lead and providing a protective hood for the stem, said arm and shield being arcuate in cross-section, and means supporting said arm and shield on said lead.
